UNITED STATES PATENT OFFICE.

WALTER ERNST, OF MOUNT GILEAD, OHIO, ASSIGNOR TO THE HYDRAULIC PRESS MANUFACTURING COMPANY, OF MOUNT GILEAD, OHIO.

CONTROL MECHANISM FOR HYDRAULIC PRESSES.

Application filed December 8, 1926. Serial No. 153,410.

REISSUED

The invention herein disclosed is particularly adapted for use with a hydraulic press of the character disclosed in my copending application Serial No. 138,416, filed September 29, 1926 but is adapted for use with other types of presses.

It is common to employ in hydraulic press mechanism a pump for forcing fluid under pressure to said press, which pump is of the type known as a variable stroke, variable and reversible discharge. A pump of this character may be seen for example in Patent 1,250,170 to Hele-Shaw et al. and is well known to those familiar with this art. In such pumps the direction of movement of the liquid discharged may be reversed and the speed may be varied simply by reciprocating a cross head or similar device from one position to another. This cross head is connected to a floating ring which may be shifted off center with relation to other elements of the pump or may be held in a central position. When in a central position the pump runs idly while when the floating ring is off center on one side the fluid under pressure will be discharged in one direction but in the opposite direction when the floating ring is moved off center on the other side.

It is unnecessary to set forth the specific construction of the pump in any more detail and the same is not illustrated herein since the present invention relates to control mechanism interposed between the pump and the press whereby the operation of the pump will be controlled as desired.

Assuming that the press is idle and that the pump is running idly a movement of the lever adjacent the press through the interposed control mechanism will cause the pump to deliver fluid under pressure and produce the press stroke of the platen of the press. When a certain resistance has been built up in the system the control mechanism will operate automatically to throw the pump into reverse and produce the return movement of the press platen. When this return movement is completed the control mechanism will be again operated to throw the pump into neutral position where it will remain with the press platen in its idle position until another pressing operation is initiated manually.

In the drawings:

Figure 1 is a side elevation of the control mechanism with the pump and press more or less diagrammatically disclosed.

Figure 2 is a view of a detail.

Figure 3 is a longitudinal section through a part of the control mechanism.

The press is herein illustrated as comprising a bed A and a top B connected by four strain rods C and having the usual table and cooperating sliding platen D operated by a main ram E. It is to be understood that this showing is merely illustrative and that various types of presses may be equipped with the control mechanism constituting the present invention.

This control mechanism comprises certain elements preferably carried by the press frame which may be referred to broadly as the controlling linkage and control mechanism which may be carried by or attached to the pump proper and constitutes the control mechanism proper.

The control linkage comprises a handle 1 carried by the press frame and normally held in intermediate position by springs 2 and 3. To the handle is connected an arm 4 pivoted to a link 5, which at its other end is pivoted to an arm 6 having a hub 7 which is loosely mounted on a shaft 8 carried by the press frame. A collar 9 is fast on said shaft and the hubs 7 and 9 have interlocking projections cut away as indicated at 10 to provide for a certain amount of lost motion in either direction of one part relative to the other. An arm 11 is fixed to the shaft 8 and is connected by a link 12 which is preferably adjustable to an arm 13 of the control mechanism proper. The shaft 8 also has an arm 14 provided with a forked end which overlies a head 15 on a rod 16 mounted to slide in a bracket 17 carried by the press and provided with an adjustable stop collar 18 adapted to be engaged by an arm 19 which terminates in an eye sliding on the rod 16 which arm is carried by the platen D and will engage the stop collar 18 at a point predetermined by the adjustment of said stop collar.

If the parts are in the position shown in Figure 1 and the lever 1 is depressed the link 5 will be raised and the arm 6 moved upwardly, which after the lost motion is taken up,

will produce a movement of the rod 8 and through the arm 11 and link 12 will move the control lever 13 in the direction of the arrow *a* and cause the pump to deliver fluid in a proper direction to initiate the pressing operation. At the termination of the downward movement of the press, the control mechanism indicated generally at F and carried by the pump G will operate to move the rod 12 as hereinafter described quickly toward the right. This will not be dangerous to the operator because this movement will merely take up the lost motion and cause no movement whatever of the lever 1 at this time, since this lever has already been released by the operator and has been returned to its central position.

When the control mechanism as just described has been reversed, the pump then delivers fluid under pressure in a direction to return the platen D to its upper position. In this upward movement the arm 19 will ultimately contact with the collar 18 which will lift the rod 16 and through the one way connection 14 and 15 will move the rod 12 toward the left in Figure 1 sufficiently to bring the control arm 13 to central position in which the pump remains idle.

The control mechanism F through which the above sequence of operations is produced will now be described. The movable cross head of the pump is represented at 20 and attached thereto is a stem 21. This stem is mounted to slide in a sleeve 22, which is hollow throughout a portion of its length and the head 23 of the stem which bears against a spring 24 enclosed in the hollowed portion of the sleeve 22. A stem 25 is screw threaded into the sleeve 22 and holds the spring 24 normally under about fifty pounds pressure.

The control lever 13 is fulcrumed at 26 to the casing of the control mechanism and is pivoted at 27 to the stem 25. The free end of the lever 13 is provided with a hardened portion 28 which is adapted to engage with a trip member 29 which is fulcrumed at 30. A strong spring 31 is coiled about the sleeve 22 and bears at one end against a fixed part and at the other against a flange on said sleeve and obviously tends to move the sleeve and the stem 25 toward the left as shown in Figure 3. This movement when permitted is limited by the engagement of a collar on the stem with an adjustable stop member 32.

The fulcrum 30 of the trip 29 is connected to a small cylinder 30' which travels horizontally on slides on top of a control member F. This cylinder may be moved and locked in desired position by means of a hand wheel 41. Trip 29 has pivoted thereto at 33 a piston 34 which slides in the cylinder 30' and has a head working in a chamber 35 of said cylinder. From this chamber a pipe 36 communicates with the main cylinder of the press so that the pressure in the chamber 35 will al-

ways be the same as that in the main press cylinder. A spring 37 bears at one end against the trip 29 and tends to hold it in engagement with the free end 28 of the control lever 13 as shown in Figure 3. The tension of this spring 37 may be adjusted by means of a hand wheel 39 carried by a flange 38 of the cylinder 30'.

Assuming that the press is in its upper position, the operator initiates the operation by moving the hand lever 1 as above described which moves the link 12 toward the left and rocks the control lever 13 about its pivot point 26 thereby moving the free end thereof toward the right. This movement will cause the upper end thereof to cam the trip 29 out of its path after which said trip snaps into the Figure 3 position and holds the control lever 13 in that position. This movement of the control lever toward the right also moves the cross head 20 and so controls the pump that fluid will be delivered under pressure to the main press cylinder. The spring 24 permits a little overtravel of the stem 25 after the stem 21 has completed its stroke in order that the free end 28 may move far enough to insure its being retained by the trip 29. The amount of movement of the lever 13 and the stem 25 will be governed by the position of the trip member 29. If the fulcrum 30 is moved by means of the hand wheel 41 toward the left the trip 29 will engage the control lever 13 at an earlier point of its movement so that the stem 25 will be moved only through a part of its full stroke which will result in the pump delivering only a partial amount of the fluid and therefore imparting slower speed to the press. This hand wheel 41 may be set for any speed desired.

Since fluid is now being delivered under the desired pressure to the main cylinder of the press, the press platen will now move until it hits a certain resistance. The pressure in the system and consequently in the chamber 35 will now build up and will ultimately overcome the tension of the spring 37 and move the piston 34 to the right, thus releasing the trip 29 from engagement with the control lever 13. The tension of this spring 37 may be varied by means of the hand wheel 39, thus varying the pressure at which the control mechanism will be operated and consequently varying the maximum pressure to be exerted by the press.

As soon as the trip 29 releases the operating lever 13 the spring 31 will cause the stem 25 to move toward the left a sufficient distance to reverse the pump and cause fluid to be discharged under pressure to the press for returning the platen to its normal position. The amount of this movement and consequently the return speed of the press may be regulated by the feeding of the stop member 32.

The press will now return at this predetermined rate of speed until the arm 19 contacts

with the stop 18 as above described which will impart a movement to the control arm 13 returning the stem 21 to the right and moving the pump into neutral position. The 5 parts will remain in such position until a second sequence of operations is initiated by a movement of the lever 1. The press will stay in upper position indefinitely so long as the 10 pump is running even if there is a leak in the system, since as soon as it starts to move downward it will release the stop collar 18 thus releasing the controlling lever 13 and permitting the spring 31 to move the stem 21 slightly, thus moving the pump to a position 15 to exert a certain pressure in a direction to return the platen to its upper position.

It may be noted that if the fulcrum point 30 is moved to the extreme right, the automatic 20 feature may be eliminated since in this case the trip 29 will never engage with the lever 13 and the press will operate like an ordinary manually operated double acting cylinder. It is also noted that the trip 29 may be provided with a hand lever 40 through 25 which it may be operated independent of the automatic mechanism if desired. It is also possible to operate the lever 1 by means of a pedal instead of by hand.

Various other detail changes may be made 30 in the precise construction without in any way departing from the spirit of the invention, which is to be regarded as limited only by the scope of the appended claims.

I claim as my invention:

35 1. A control mechanism adapted to be operatively connected to a hydraulic circuit including a reversible variable discharge pump and a hydraulic press having a movable platen; said mechanism comprising a 40 device adapted to occupy three positions, means for moving the device from the first to the second position to cause the pump to discharge so as to produce the pressing movement of the platen, pressure controlled means 45 for thereafter moving the device from the second to the third position to reverse the discharge of the pump and produce the return movement of the platen, and automatic means for thereafter moving the device from the 50 third to the first position to place the pump in a neutral position.

2. A control mechanism adapted to be operatively connected to a hydraulic circuit including a reversible variable discharge pump 55 and a hydraulic press having a movable platen; said mechanism comprising a device adapted to occupy three positions, means for moving the device from the first to the second position to bring about the pressing movement 60 of the platen, means for detaining the device in such position, means controlled by the pressure in the circuit for releasing said detaining means, and means for moving said device when released from the detaining 65 means from the second to the third position

to produce the return movement of the platen. 3. A control mechanism adapted to be operatively connected to a hydraulic circuit including a reversible variable discharge pump and a hydraulic press having a movable platen; 70 said mechanism comprising a device adapted to occupy three positions, means for moving the device from the first to the second position to bring about the pressing movement of the platen, a spring actuated detent for detaining 75 the device in such position, means controlled by the pressure in the circuit for releasing said detent, and spring means for moving said device when released from the detaining means from the second to the third position 80 to produce the return movement of the platen.

4. A control mechanism adapted to be operatively connected to a hydraulic circuit including a reversible variable discharge pump and a hydraulic press having a movable platen; 85 said mechanism comprising a device adapted to occupy three positions, means for moving the device from the first to the second position to bring about the pressing movement of the platen, a spring actuated de- 90 tent for detaining the device in such position, means for varying the normal position of the detent to thereby vary the position of the device and the consequent speed of the press, and means controlled by the pressure in the 95 circuit for releasing said detent to permit the device to move to another position.

5. A control mechanism adapted to be operatively connected to a hydraulic circuit including a reversible variable discharge pump 100 and a hydraulic press having a movable platen; said mechanism comprising a device adapted to occupy three positions, means for moving the device from the first to the second position to bring about the pressing movement of the platen, means for detaining the device in such position, means controlled by the pressure in the circuit for releasing the device from the detaining means, means for moving the device when released from the sec- 105 ond to the third position, and means for vary- 110 ing the third position of the device and the consequent speed of the return movement of the platen.

6. A control mechanism adapted to be operatively connected to a hydraulic circuit including a reversible variable discharge pump and a hydraulic press having a movable platen; said mechanism comprising a device 120 adapted to occupy three positions, means for moving the device from the first to the second position to bring about the pressing movement of the platen, means for detaining the device in such position, means for varying the normal position of the detaining means to thereby vary the position of said device and the consequent speed of the platen, means controlled by the pressure in the circuit for releasing the device from the 125 detaining means, means for moving the de- 130

- vice when released from the second to the third position, and means for varying the third position of the device and the consequent speed of the return movement of the platen.
7. A control mechanism adapted to be operatively connected to a hydraulic circuit including a reversible variable discharge pump and a hydraulic press having a movable platen;
- 10 manually operable means adjacent said press for moving the device from the first to the second position to bring about the pressing movement of the platen, means controlled by the pressure in the circuit for moving the device from the second to the third position to produce the return movement of the platen, and means controlled by the return movement of the platen for moving the device from the third to the first position to place the pump in a neutral position.
8. A control mechanism adapted to be operatively connected to a hydraulic circuit including a reversible variable discharge pump and a hydraulic press having a movable platen; manually operable means adjacent said press for moving the device from the first to the second position to bring about the pressing movement of the platen, means controlled by the pressure in the circuit for moving the device from the second to the third position to produce the return movement of the platen, means controlled by the return movement of the platen for moving the device from the third to the first position to place the pump in a neutral position, and means for varying the second and third positions of said device.
9. A control mechanism adapted to be operatively connected to a hydraulic circuit including a reversible variable discharge pump having a control member and a hydraulic press having a movable platen; said mechanism comprising a movable device connected to said control member, means for moving said device to a position to produce the pressing movement of the platen, a spring operated detent for said device, a piston connected to the detent and operated by the pressure in the circuit for releasing said detent, and means for thereafter moving said device to a position to produce the return movement of the platen.
10. A control mechanism adapted to be operatively connected to a hydraulic circuit including a reversible variable discharge pump having a control member and a hydraulic press having a movable platen; said mechanism comprising a movable device connected to said control member, means for moving said device to a position to produce the pressing movement of the platen, a spring operated detent for said device, a piston connected to the detent and operated by the pressure in the circuit for releasing said detent, and means for varying the predetermined pressure at which the detent will be released.
11. A control mechanism adapted to be operatively connected to a hydraulic circuit including a reversible variable discharge pump having a control member and a hydraulic press having a movable platen; said mechanism comprising a movable device connected to said control member, means for moving said device to a position to produce the pressing movement of the platen, a spring operated detent for said device, a piston connected to the piston and operated by the pressure in the circuit for releasing said detent, means for varying the predetermined pressure at which the detent will be released, and means for thereafter moving said device to a position to produce the return movement of the platen.
12. A control mechanism adapted to be operatively connected to a hydraulic circuit including a reversible variable discharge pump and a hydraulic press having a movable platen; said mechanism comprising a lever adapted to be connected to and control said pump, a link extending from the lever to a point adjacent the press, a rock shaft connected to said link, and manually operable lever-actuating means having a lost motion connection with said rock shaft.
13. A control mechanism adapted to be operatively connected to a hydraulic circuit including a reversible variable discharge pump and a hydraulic press having a movable platen; said mechanism comprising a lever adapted to be connected to and control said pump, a link extending from the lever to a point adjacent the press, a rock shaft connected to said link, manually operable lever actuating means having a lost motion connection with said rock shaft, and means adapted to be operated by the movement of the platen having a one way connection with the rock shaft for moving the lever to neutral position.
14. In combination, a reversible, variable capacity pump, a double acting hydraulic motor, means forming with the pump and motor a hydraulic circuit, mechanism for varying the pump capacity from zero in either direction of flow, means for moving said mechanism from zero capacity position to pumping position whereby the motor piston is made to advance, means responsive to the attainment of a predetermined pressure on the motor piston for reversing said mechanism whereby the piston is made to perform a return stroke, and means responsive to the attainment by the piston of a predetermined position in the return stroke for moving said mechanism to zero capacity position.
15. The combination with a hydraulic press including a stationary table and a reciprocating platen movable towards and from the table, of a reversible pump, means forming with the press and pump a hydraulic circuit, and controlling means operatively connected

with the pump and circuit for moving the platen towards the table and responsive to the pressure built up in the circuit during said movement of the platen for automatically reversing the pump and the platen irrespective of the position of the platen relative to the table.

16. The combination with a hydraulic press including a stationary table and a reciprocating platen movable towards and from the table, of a reversible pump, means forming with the press and pump a hydraulic circuit, and controlling means operatively connected with the pump and circuit for moving the platen towards and from the table and including a control lever operatively connected with the pump for controlling the direction of fluid in the circuit, a trip for holding said lever in one extreme position for directing the fluid to move the platen towards the table, means responsive to the built up pressure in the circuit during said movement of the platen to release said trip, and means for moving the control lever to the other extreme position upon release of said trip whereby the direction of fluid in the circuit will be reversed.

17. The combination with a hydraulic press including a stationary table and a reciprocating platen movable towards and from the table, of a reversible pump, means forming with the press and pump a hydraulic circuit, and controlling means operatively connected with the pump and circuit for moving the platen towards and from the table and including a control lever operatively connected with the pump for controlling the direction of fluid in the circuit, a trip for holding said control lever in one extreme position for directing the fluid to move the platen towards the table, means responsive to the built up pressure in the circuit during said movement of the platen to release said trip, said responsive means including a pressure chamber operatively connected to the circuit, and a piston in said chamber and connected to the trip, and means for moving the control lever to the other extreme position upon release of said trip whereby the direction of fluid in the circuit will be reversed.

18. The combination with a hydraulic press including a stationary table and a reciprocating platen movable towards and from the table, of a reversible pump, means forming with the press and pump a hydraulic circuit, controlling means operatively connected with the pump and circuit for moving the platen towards and from the table and including a control lever operatively connected with the pump for controlling the direction of fluid in the circuit, a trip for holding said lever in one extreme position for directing the fluid to move the platen towards the table, means responsive to the built up pressure in the circuit during said movement of the

platen to release said trip, said responsive means including a pressure chamber operatively connected to the circuit, and a piston in said chamber and connected to the trip, means for moving the lever to the other extreme position upon release of said trip whereby the direction of fluid in the circuit will be reversed, and means controlled by the platen for moving the control lever to an intermediate position for placing the pump in neutral position.

19. The combination with a hydraulic press including a stationary table and a reciprocating platen movable towards and from the table, of a reversible pump, means forming with the press and pump a hydraulic circuit, controlling means operatively connected with the pump and circuit for moving the platen towards the table and responsive to the pressure built up in the circuit during said movement of the platen for automatically reversing the pump and the platen irrespective of the position of the platen relative to the table, and means connected to the controlling means and operated by the platen during the reverse movement thereof to automatically place the pump in neutral position and thereby stop the movement of the platen at the end of one complete cycle.

20. The combination with a hydraulic press including a stationary table and a reciprocating platen movable towards and from the table, of a reversible pump, means forming with the press and pump a hydraulic circuit, and controlling means operatively connected with the pump and circuit for moving the platen towards and from the table and including a control lever operatively connected with the pump for controlling the direction of fluid in the circuit, a trip for holding said lever in one extreme position for directing the fluid to move the platen towards the table, means responsive to the built up pressure in the circuit during said movement of the platen to release said trip, and means for moving the control lever to the other extreme position upon release of said trip whereby the direction of fluid in the circuit will be reversed, and means connected to the control lever and operated by the platen during the reverse movement thereof to automatically move the lever to an intermediate position and thereby place the pump in neutral position and stop the movement of the platen at the end of one complete cycle.

21. The combination with a hydraulic press including a stationary table and a reciprocating platen movable towards and from the table, of a reversible pump, means forming with the press and pump a hydraulic circuit, and controlling means operatively connected with the pump and circuit for moving the platen towards and from the table and including a control lever operatively connected with the pump for controlling the direction of fluid

- in the circuit, a trip for holding said lever in one extreme position for directing the fluid to move the platen towards the table, means responsive to the built up pressure in the circuit during said movement of the platen to release said trip, and means for moving the control lever to the other extreme position upon release of said trip whereby the direction of fluid in the circuit will be reversed, and
- 10 means connected to the control lever and operated by the platen during the reverse move-

ment thereof to automatically move the lever to an intermediate position and thereby place the pump in neutral position and stop the movement of the platen at the end of one complete cycle, and manually operable means connected to the control lever for moving the same for engagement by the trip. 15

In testimony whereof, I have hereunto subscribed my name.

WALTER ERNST.
